UNITED STATES PATENT OFFICE.

JOHN G. LEE, OF LITTLETON, NEW HAMPSHIRE.

WRENCH.

1,175,463.

Specification of Letters Patent.

Patented Mar. 14, 1916.

Application filed June 21, 1915. Serial No. 35,258.

To all whom it may concern:

Be it known that I, JOHN G. LEE, a citizen of the United States, and a resident of the city of Littleton, in the county of Grafton and State of New Hampshire, have invented certain new and useful Improvements in Wrenches; and I do hereby declare that the following is a full, clear, and exact description of the same, reference being had 10 to the accompanying drawings, and to the numerals of reference marked thereon, which form a part of this specification.

The great objection to adjustable wrenches is the difficulty experienced and time required in effecting a proper adjustment thereof for the purpose required. This invention, however, relates to a wrench constructed for adjustment by merely moving the handle with respect to the head of the 20 wrench, so that after engaging the head upon an object, movement of the handle in a certain direction serves to tighten the head of the wrench upon the object, the head loosening again from the object when the 25 handle is moved in an opposite direction, so that use of the device in a confined space is thus facilitated.

It is an object therefore of this invention to construct a wrench the head of which is 30 adjustable to fit various objects, the releasing and locking thereof being effected by movement of the wrench handle.

It is furthermore an important object of this invention to construct a wrench provided 35 with a spring impelled head pivotally connected to a handle with a co-acting rack and ratchet segment provided between said head and handle to lock the head in an adjusted position for use.

40 It is furthermore an object of this invention to construct a wrench having a handle with an adjustable head pivotally associated therewith, said head, when swung into a certain position, free to move into any desired 45 position of adjustment and when moved toward a position of alinement with the handle being interlocked and rigidly held in position, and with stress applied to the handle, being clamped tightly upon the object 50 on which it is engaged.

It is finally an object of this invention to 55 construct an adjustable wrench which may be released or tightened upon an object by movement of the handle, and with resilient means acting normally to hold the parts in interlocked adjusted position.

The invention (in a preferred form) is illustrated in the drawings and hereinafter more fully described.

In the drawings: Figure 1 is a side elevation of a device embodying the principles of my invention. Fig. 2 is a fragmentary view partly in section and partly in elevation of one end thereof. Fig. 3 is a front edge view of the device. Fig. 4 is a detail 60 section taken on line 4—4 of Fig. 2. Fig. 5 is a detail of the resilient means forming a part of the device. Fig. 6 is a view similar to Fig. 2, illustrating the adaptation of an auxiliary element to the device. Fig. 7 65 is an elevational view of the auxiliary element.

As shown in the drawings: The reference numeral 1, indicates the handle of the wrench, the end of which is bifurcated or 70 enlarged and curved to form integrally connected yoke arms 2. Extending through said yoke arms 2, is a pin 3, and rigidly secured thereon or formed integral with said yoke arms, as desired, is a toothed ratchet 75 element 4. Pivotally mounted upon said pin 3, is an interiorly recessed and apertured clamping or jaw member 5, and as clearly shown in Fig. 1, said yoke arms 2, are cut away to receive the extended portions 6, of 80 the clamping member disposed on each side of the ratchet element 4, through which the pin 3, extends. Extending through the apertured portion of said clamping jaw member 5, and downwardly between the 85 yoke arms 2, of the handle, is a straight shank portion 7, of another clamping jaw 8, which is integrally formed on the outer end of said shank. As clearly shown in Figs. 2, 3, and 6, one edge of said shank member 90 95 90 is provided with a series of ratchet teeth 9, to co-act with the ratchet element 4. Secured by means of small screws or otherwise upon flattened portions of the yoke arms 2, is a yoke shaped spring member 10, which bears against that end of said clamping member 5, farthest removed from the pivot pin 3, to normally impel the same and the clamping jaw 8, and shank 7, therewith toward or beyond a position of alinement with 100 the handle 1.

In the illustration shown in Figs. 6 and 7, I have provided an auxiliary plate 11, having pins 12, secured therein, and adapted to fit apertures 13, in the inner clamping jaw 5, to hold said plate in position thereon. The outer surface of said plate is 110

serrated to enable the same to grip tightly upon round or smooth objects, so that the device so used, may be utilized as a pipe wrench.

5 The operation is as follows: The device as illustrated in the figures, is shown in locked position, and in order to release the same for adjustment of the clamping jaw or head 8, it is necessary to swing the associated jaws 5 and 8, inwardly in a clockwise direction with reference to Fig. 1, against the stress of the spring 10, so that the teeth 9, in the edge of the shank 7, of the jaw 8, will be disposed in a position to clear the 15 fixed teeth of the ratchet element 4. The jaw member 8, may then be adjusted inwardly or outwardly, as desired, to the necessary extent, and the wrench as thus used, referring to Fig. 1, is rotated in a 20 clockwise direction by the handle 1, thus tending to bring the shank 7, again into alinement with the handle 1, or in fact moving the same slightly beyond an alined position, so that the teeth of the ratchet 25 element 4, tightly engage the teeth 9, locking the jaw member 8, in a fixed position, and in fact tending to draw the same inwardly, thus clamping the object between the jaws 5 and 8. The movement of the 30 handle 1, in an opposite direction of rotation with respect to the jaw elements, of course serves to release the same from the object.

In the form of device illustrated in Figs. 35 6 and 7, I have shown a means of attaching a serrated plate 11, to one of the jaws of the device, although obviously two such plates may be provided, one for attachment to each of the jaws, which act to bite into a 40 smooth object such as the surface of a pipe, permitting the wrench to be readily used where occasion requires as a pipe wrench. The frictional fit of the pins 12, in the recesses 13, provided in the jaw member, 45 serves to retain the plate rigidly associated therewith.

I am aware that various details of construction may be varied through a wide range without departing from the principles of this invention, and I therefore do 50 not purpose limiting the patent granted otherwise than necessitated by the prior art.

I claim as my invention:

55 1. In a device of the class described a handle member, yoke arms integrally formed thereon, a jaw member pivoted

thereon, another jaw member slidably in said first mentioned jaw member, and means integral with said yoke arms to lock said 60 jaws from movement with respect to one another and with respect to said handle member.

2. In a device of the class described a yoked handle member, a jaw member pivoted thereon, another jaw member slidably in said first mentioned jaw member, and means rigidly secured on said yoked handle member acting automatically to lock said jaws from movement with respect to one 70 another and with respect to said handle member.

3. In a device of the class described the combination with a handle, yoked arms integral therewith, of a jaw member pivotally mounted on said arms, another jaw member slidably associated with said first mentioned jaw member, a toothed element rigidly connected with said second mentioned jaw member, and ratchet means integral with said yoked arms adapted to coact with said toothed element to lock said jaws in adjusted position with respect to one another and with respect to said handle. 75

4. In a device of the class described the combination with a handle having arms integrally formed at one end thereof, of jaw members pivotally associated with said arms, interlocking means between said handle and said jaw members acting when said 90 handle is rotated with respect thereto to draw said jaw members into clamping relation with one another and a spring rigidly secured upon said arms adapted to normally impel said jaw members into a 95 position of alinement with said handle.

5. In a device of the class described the combination with a bifurcated handle, of jaw members slidably associated with one another and pivotally connected to the bifurcated and offset handle, and toothed means integral with said bifurcated handle acting automatically to draw said jaw members into clamping relation and hold the same rigid with respect to said handle when 105 force is applied to said handle and the jaws are engaged upon an object.

In testimony whereof I have hereunto subscribed my name in the presence of two subscribing witnesses.

JOHN G. LEE.
